Primary Examiner — Mark A Goodwin(74) *Attorney, Agent, or Firm* — DeLio, Peterson & Curcio, LLC; Thomas E. Ciesco(57) **CLAIM**

The ornamental design for a “door lock escutcheon,” as shown and described.

DESCRIPTION

FIG. 1 is a left front top perspective view of the “door lock escutcheon” design according to our invention;

FIG. 2 is a front elevational view of the “door lock escutcheon” shown in FIG. 1;

FIG. 3 is a top plan view of the “door lock escutcheon” shown in FIG. 1;

FIG. 4 is a bottom plan view of the “door lock escutcheon” shown in FIG. 1;

FIG. 5 is a left side elevational view of the “door lock escutcheon” shown in FIG. 1; and,

FIG. 6 is a right side elevational view of the “door lock escutcheon” shown in FIG. 1.

The back view of the “door lock escutcheon” which is not shown forms no part of the design.

Portions of the door lock escutcheon are shown in phantom lines and form no part of the design.
